HYDRAULIC TRANSMISSION MEANS

Filed Nov. 13, 1939

UNITED STATES PATENT OFFICE

2,276,895

HYDRAULIC TRANSMISSION MEANS

Heinrich Franz Vosseler and Harry Albert William Pierard, Stratford, New Zealand, assignors to said Vosseler, said Pierard, William Henry Young, Hawera, New Zealand, and Bertram George Aiken Harkness, New Plymouth, New Zealand

Application November 13, 1939, Serial No. 304,250
In New Zealand November 18, 1938

3 Claims. (Cl. 103—11)

The invention relates to transmission means wherein a hydraulic fluid is employed to perform useful work, and has for its object, the provision of improved transmission means, designed to give in a comparatively simple manner, increased flexibility over known forms of transmissions in the machine or apparatus operated by the fluid, combined with ability to reverse the action thereof, and also to utilize same to obtain a braking effect.

The improved means provided by the invention comprise a fluid circuit having incorporated therein, a plurality of pumping units of different output capacities, and each of which is adapted to operate continuously at full output; and a flow control valve and an exhaust control valve formed and capable of being operated to enable the full output of all of the pumping units to be utilized to perform work or to be diverted without performing work, or for any portion of said output to be utilized to perform work and the remainder to be diverted without performing work.

The pumping units can comprise gear or cog wheel pumps, and the control valves can be of the open ended hollow barrel type containing radial ports and operable in bodies containing radial ports, said barrels being coupled or geared together to operate in unison.

In the accompanying drawing, in conjunction with which the invention will be more particularly described,

Figure 1 illustrates diagrammatically, the general arrangement of the means employed,

Figure 2 illustrates a modification,

Figure 3 is a vertical sectional view of one of the control valves employed, and

Figure 4 is a sectional plan view on the line 4—4, Figure 3, while

Figures 5 and 6 illustrate the arrangements of the ports in the barrels of the flow control valve and the exhaust control valve, respectively.

In carrying out the invention hydraulic fluid is drawn from a tank or reservoir 1 and placed under pressure by pumps of different capacities, either built and driven separately or combined so as to be capable of being driven as a single apparatus having units of different capacities, any form of pump suitable for the purpose being utilized.

A convenient form of pump can comprise a gear or cog wheel pump having incorporated therein separate pumping units of different capacities, and all driven together from and by the same motor or power unit operated shaft 2,

Thus a gear or cog wheel pump suitable for the purpose of the invention can comprise three pumping units, 3, 4, 5, unit 4 having twice the capacity of unit 3, while unit 5 has twice the capacity of unit 4 and four times the capacity of unit 3, said units 3, 4, 5 or pumps, if separate pumps are used, having inlets 6, 7, 8 respectively in communication through a pipe 21 with the fluid tank or reservoir 1, and outlets 9, 10, 11 respectively, in communication through pipes 23, 24, 25, with geared together flow control, and exhaust control valves 12 and 13.

The flow and the exhaust control valves 12 and 13 each comprises a hollow barrel 14 open at the bottom, (Figures 3 and 4) rotatable in a body 15 containing ports 16, 17, 18 adapted to be connected with the delivery sides of the pumping units, or pumps 3, 4, 5, the interior of the exhaust control valve 13 also being in communication through the lower end of its barrel 14, pipes 19, 20, tank or reservoir 1 and pipe 21, with the intakes 6, 7, 8 of the pumping units or pumps 3, 4, 5 while the interior of the flow control valve 12 is also in communication through the lower end of its barrel 14 and the pipe 22 with the machine or apparatus to be operated, the valve barrels 14 having formed therein radial ports (Figures 5 and 6) capable of being made to register with the ports 16, 17, 18 in the bodies 15 in communication with the delivery sides of the pumping units or pumps 3, 4, 5.

The connecting pipes 23, 24, 25 between the delivery sides 9, 10, 11 of the pumping units or pumps 3, 4 and 5 and the control valves 12, 13 are branched so as to communicate with each of the latter, the branches 23a, 24a and 25a leading to the exhaust control valve 13, and the ports in the valve barrels 14 are formed and arranged so that when the flow control valve 12 is open to the delivery side of a particular pumping unit or pump 3, 4 or 5, the exhaust valve 13 is closed to that pumping unit or pump 3, 4 or 5, whereby fluid put under pressure by the selected unit or pump is passed all through the flow control valve 12 to the machine or apparatus it is intended to operate, and from which it passes via the return pipe or connection 20 to the tank or reservoir 1 for re-use.

Each pumping unit or pump 3, 4, 5, delivers or discharges fluid at its full capacity continuously, and the ports in the barrel 14 of the exhaust control valve 13 are arranged in relation to the ports in the barrel 14 of the flow control valve 12, so that when any combination of ports in the barrel 14 of the flow control valve 12 is open through

the ports 16, 17, 18 of said valve to the discharge sides 9, 10, 11 of the pumping units or pumps 3, 4, 5, and the latter are passing fluid through the connections 23, 24, 25 to and through the flow control valve 12, fluid in excess of that passed under pressure to and through the flow control valve 12, is diverted through such of the branches 23a, 24a, 25a of said connections 23, 24, 25, as are open to the exhaust control valve 13, to and through the latter to pass into the exhaust or return pipe 20 from the machine or apparatus being operated, and be returned to the tank or reservoir 1, for re-use, the diverted fluid owing to it not taking any of the load only being under such pressure as is necessary to cause same to circulate.

The ports in the barrels 14 of the valves 12, 13 are of different sizes in accordance with the capacities of the pumping units or pumps 3, 4, 5 they serve, ports adapted to be put in communication with the pumping unit or pump of the smallest capacity being smaller than the other ports, while ports adapted to be put in communication with or to serve the pumping unit or pump of greatest capacity being larger than the other ports, while intermediate sized ports for serving pumping units or pumps having capacities between the units or pumps of smallest and greatest capacities, are also provided in the barrels.

By arranging the different sized ports in the valve barrels 14, in varying combinations, and by providing that excess (if any) of fluid over that capable of being passed by a selected combination of ports in the flow control valve 12, is by-passed via the exhaust control valve 13 to the return pipe 20 to the fluid tank or reservoir 1, the pumping units or pumps 3, 4, 5 are all enabled to be run continuously at full capacity, while the transmission of fluid to perform work can be varied considerably, and merely by the operation of the control valves 12, 13, to obtain a desired result in the operation of the machine or apparatus, within the limits of said control valves.

Explaining further the operation of the control valves 12, 13, and referring to Figures 5 and 6 which represent the barrels 14 of the flow control valve 12 (Figure 5) and the exhaust control valve 13 (Figure 6), opened out, the bodies 15 of said valves 12, 13 contain identical ports 16, 17 and 18, arranged in vertical rows, the smallest ports 16 serving the pumping unit or pump 3 of smallest capacity, the intermediate size ports 17 serving the intermediate pumping unit or pump 4, while the largest ports 18 serve the pumping unit or pump 5 of greatest capacity.

Each barrel 14 has formed therein, a horizontal row of ports, any one of which will fully open the port 16 in the body 15 in which it works, also a horizontal row of ports any one of which will fully open the port 17 in the body 15 in which it works, and a further horizontal row of ports, any one of which will fully open the port 18 in the body 15 in which it works.

The ports in the barrels 14 are also arranged in vertical rows, A, B, C, D, E, F, G, and said barrels 14 are coupled or geared together as at 33 (Figure 1), so that when the vertical row A of ports in the barrel 14 of the pressure control valve 12 (Figure 5) is presented to ports 16, 17 and 18 of said valve to fully open same, the blank portion of the barrel 14 of the exhaust control valve 13 (Figure 6) is presented to the ports 16, 17, 18 thereof and fully closes the said valve 13, whereby the total fluid output of the

pumping units or pumps 3, 4, 5, is passed to the pipe 22 and utilized, there being no exhaust via the valve 13.

If however, the vertical row B of ports in the barrel 14 of the valve 12 (Figure 5) is presented to the ports 16, 17 and 18 thereof, it will be seen that only the outputs of pumping units or pumps 4 and 5 are allowed to pass via valve 14 to the pipe 22, the output of unit or pump 3 being diverted via branch 23a to pass via the port in row G of barrel 14 (Figure 6) of the exhaust control valve 13 through the latter and pipes 19, 20 to the tank or reservoir 1.

A two way valve 26 inserted in the fluid delivery pipe 22 from the pressure control valve 12 to the machine or apparatus being operated, and also in the fluid return or exhaust pipe 20 from the latter, can be operated to reverse the functions of the inlet and the exhaust ports of the machine or apparatus, and so provide for reverse operation thereof.

Also by providing a shut off cock or valve 27 in the fluid return pipe 20 to the tank or reservoir 1, the flow of fluid to the latter from the machine or apparatus can be controlled or regulated to give a braking action or effect on or to said machine or apparatus.

A relief valve 28 suitably loaded can be provided in the fluid return pipe 20 to the tank or reservoir 1, and also the fluid supply connections 23, 24, 25 between the pumping units or pumps 3, 4, 5, and the control valves 12 and 13, can be provided with relief valves 29, 30, 31 which are connected by pipes 29a, 30a, 31a with the fluid tank or reservoir 1, while the relief valve 28 in the fluid return pipe 20 aforesaid, is fitted with a by-pass 32 to beyond the shut off cock 27 in said return pipe.

As illustrated in Figure 2, instead of fluid from the valve 13 also fluid exhausted from the machine or apparatus being operated, passing through the tank or reservoir 1, and the pumping units or pumps 3, 4 and 5 drawing their supply from the latter, the pipe 20 can be connected directly with the intakes 6, 7 and 8 of the pumping units or pumps 3, 4 and 5, thereby providing practically an enclosed circuit, and in this case the tank or reservoir 1 would be connected by a connection 34 containing a check or non-return valve 35, allowing fluid to enter, but not to leave the circuit, while excess pressure due to heat expansion or other causes can be allowed to escape back into the tank or reservoir 1 via a spring loaded relief valve 36 on a by-pass 37.

The transmission means herein described are particularly adapted for use with engines of the rotary type, although they can quite well be used with engines of the reciprocating type.

What we do claim and desire to obtain by Letters Patent of the United States of America is:

1. Hydraulic transmission means including a reservoir in combination with a fluid circuit, a series of pumping units communicating with said reservoir and each succeeding unit having twice the output capacity of the preceding unit and all of said units being adapted to operate at continuously full capacity to draw fluid from said reservoir, branched discharge pipes extending from each unit, each succeeding discharge pipe having twice the size of the preceding pipe to conform to the output capacity of its corresponding pumping unit, flow control valve means arranged at one branched end of said discharge pipes and exhaust control valve means arranged

at the other branched end of said discharge pipes, said valve means adapted to operate in unison whereby the pumping units may be regulated so that the full capacity is utilized for work or diverted back to said reservoir, or so that any portion of the output can be utilized for work and the remainder diverted back to the reservoir without performing work.

2. Hydraulic transmission means as claimed in claim 1, in which the control valve means includes body members having a plurality of inlet ports in communication with and having the same capacity as the discharge pipes, and rotatable hollow barrels arranged within the body members, open at their lower ends, and having a plurality of radial ports of the same size as the inlet ports of the body members.

3. Hydraulic transmission means as claimed in claim 1, in which the flow control valve means

and the exhaust control valve means each includes a hollow body having a plurality of inlet ports communicating with and of the same capacity as the discharge pipes, a rotatable hollow barrel arranged within each body member, open at its lower end and having a plurality of radial ports of the same size as the inlet ports of the body member, the radial ports of the hollow barrel of the flow control valve means being placed in an opposite arrangement to the radial ports of the hollow barrel of the exhaust valve control means whereby an output regulation is obtained which varies from complete pressure output to a complete exhaust output with intermediate arrangements of any portion of the output being utilized for pressure and the remainder diverted through the exhaust.
